UNITED STATES PATENT OFFICE.

CLAUDE E. MENTZER, OF DENVER, COLORADO, ASSIGNOR OF FORTY-NINE ONE-HUNDREDTHS TO LEON A. FREEMAN, OF DENVER, COLORADO.

ELECTRIC TIME-SWITCH.

No. 825,230.

Specification of Letters Patent.

Patented July 3, 1906.

Application filed December 30, 1905. Serial No. 294,013.

To all whom it may concern:

Be it known that I, CLAUDE E. MENTZER, a citizen of the United States, residing in the city and county of Denver and State of Colorado, have invented certain new and useful Improvements in Electric Time-Switches; and I do declare the following to be a full, clear, and exact description of the invention, such as will enable others skilled in the art to 10 which it appertains to make and use the same, reference being had to the accompanying drawings, and to the characters of reference marked thereon, which form a part of this specification.

15 My invention relates to improvements in electric time-switches or means for controlling an electric circuit whereby the circuit is closed and broken at will.

20 The invention is more especially intended for use in making and breaking an electric-light circuit at predetermined intervals.

It is well known that in business establishments it is necessary that the illumination of the building employed in connection 25 therewith should begin and cease at certain hours of the day.

My object is to provide an apparatus which may be set to turn the lights on and off at such intervals as may be desired.

30 The apparatus includes a time-measuring and time-indicating motor, together with a time-indicating dial and pointer connected and moving with a revoluble spindle actuated by the motor mechanism, a contact moving 35 in unison with the hand or indicator and engaging a ring composed of three parts, one part being of insulating material and another part being a continuous ring composed of conducting material, as metal, while the 40 other part is a segmental member composed of a series of contact-plates, the number employed and their arrangement being determined by the period during which the circuit is required to be closed and the particular 45 hours during which this condition must exist.

Having briefly outlined my improved construction as well as the construction it is intended to perform, I will proceed to describe 50 the same in detail, reference being made to the accompanying drawings, in which is illustrated an embodiment thereof.

In the drawings, Figure 1 is a front view of my improved electric time-switch. Fig. 2 is 55 a similar view showing the dial-carrying door open. Fig. 3 is a section taken through the

device, the motor mechanism being shown in elevation. Fig. 4 is an enlarged fragmentary detail view of the mechanism. Fig. 5 is a section taken on the line 5-5, Fig. 4. Fig. 6c 6 is a detail view of a toothed wheel forming a part of the mechanism. Fig. 7 is a sectional view illustrating a modified form of construction.

The same reference characters indicate the 65 same parts in all the views.

Let the numeral 5 designate a suitable casing, to which is hinged a door 7, provided with a transparent plate 8 and a dial 9, located inside the door and provided with numerals to indicate hours.

The numerals on the upper half of the dial (see Fig. 1) are supposed to indicate time from six o'clock at night to six in the morning, while the numerals on the lower half of 75 the dial are supposed to indicate time from six in the morning until six in the evening. These numerals therefore are arranged for the entire twenty-four hours.

The central part of the dial is provided 80 with a sleeve 10, adapted when the door is closed to turn with a centrally-located spindle 12, forming a part of the motor mechanism, the same being journaled in vertical plates 13 and 14, located within the casing 85 and secured to the wall thereof. The sleeve 10 is provided at its outer extremity with a hand or pointer 15, adapted when the motor is in operation to move in suitable proximity to the numerals on the dial, as disclosed in 90 Fig. 1.

Attention is called to the fact that the transparent plate 8 of the dial is provided at its outer edge with a metal rim 8^a, the same being hinged at 8^c to swing outwardly independently of the opening movement of the door. When closed, this auxiliary door is held in place by a spring-catch 8^d, mounted on the body of the door. It is only necessary to open the entire door when for any reason 100 it is desirable to gain access to certain parts of the motor mechanism. As shown in the drawings, the sleeve 10 is angular in cross-section. Hence the outer extremity of the spindle 10 should be of corresponding shape to permit the sleeve to slide on and off at pleasure, the two parts being thus arranged to rotate in unison.

To the spindle 12 and inside of the dial or within the closed chamber of the casing a contact-arm 16 is made fast to the spindle by a screw 17, passing through the hub or sleeve

16^a of the arm. This arm is provided at its outer extremity with an insulating-piece 17^a, to which is pivotally connected a contact 18, engaged by a spring 19, whose normal tendency is to force the contact 18 outwardly against the inner periphery of the ring 20, whose central portion 21 is composed of insulating material. The inner portion 22 consists of an unbroken plate of conducting material, as metal, and whose outer part is composed of movable contact-plates 23. As shown in the drawings, there should be one of these plates 23 for each hour of the day. The contact 18 is of sufficient width to bridge the space between the metal ring member 22 and the contact-plates 23.

One of the wires, which I will designate A, of the inner circuit leads to the continuous metal ring 22, while the wire B of the internal circuit leads to one of the segmental contact members 23. Hence the contact 18 as it moves around within the periphery of the ring 20 is always in engagement with the contact 22 and is further in engagement with the segmental plates 23 wherever they are applied to the ring 20.

Assuming that the plates 23 are arranged as shown in Fig. 2 and assuming also that the figures designating hours on the dial are arranged in the same manner as in Fig. 1, as soon as the contact 18 reaches a point on the ring 20 where the contact-plates 23 commence the circuit will be closed and remain closed until the contact reaches the part of the ring 20 containing no contact-plates 23, when the circuit will be broken and the lights go out.

If the number of plates disclosed in Fig. 2 is employed, the circuit will be closed from between five and six o'clock until twelve o'clock at night, since, as heretofore stated, the figures on the upper half of the dial are supposed to indicate time from six p. m. until six a. m., while those on the lower half time from six a. m. to six p. m. The contact-plates are preferably connected with links or parts 23^a, composed of conducting material, as metal, in order to insure perfect electric contact between the adjacent segmental plates in case it should happen that the plates were not in actual contact with each other. The conductors A and B of the internal circuit lead to binding-posts C and D, respectively, from which lead wires or conductors E and F to the respective poles of the electrical source. (Not shown.)

The ring 20 is suitably supported upon the plate 13 of the casing, this connection being made, as shown in the drawings, by means of screws 24 passed through lugs 25 formed on the insulating member 21, and entering the plate or partition 13. This screw passes through a spacing-sleeve 26, interposed between the lug 25 and the plate 13, whereby the ring is suitably supported.

As heretofore indicated, the hand 15 of the contact-arm 16 may be actuated by suitable mechanism arranged to measure time. This mechanism should be of sufficient strength for the purpose. As shown in the drawings, to the spindle 12 within the casing is secured a relatively large gear 27, meshing with a pinion 28, fast on a short spindle 29, journaled in the plate 14 and having a pinion 30 on its inner extremity. This pinion 30 meshes with a larger gear 31, fast on a spindle 32 and provided with a pinion 33, meshing with a larger gear 34, fast on a shaft 35, with which is connected one extremity 36 of a coil-spring 37, the opposite extremity of the spring being attached to a post 38, as shown at 39, the post 38 being made fast to the casing. Also to the spindle 35 is attached a winding-gear 40, meshing with a pinion 41, made fast to a key-spindle 42, fashioned at its outer extremity as shown at 43, to receive a key. (Not shown.) The pinion 33 is connected with a spindle 32 in such a manner that during the winding operation of the motor-spring the pinion 33 will turn idly on its spindle. When, however, the motor-spring acts to operate the gearing, the movement of the pinion 33 will also move the spindle 32 and the train of gears connected therewith. Any suitable construction may be employed to accomplish this end. The construction which I prefer to use is that shown in Fig. 6 of the drawings, in which a curved dog 33^a is located in a recess formed partly in the spindle 32 and partly in the pinion. This construction is so arranged (see Fig. 6) that when the pinion is turned in the direction of arrow b it will also carry the spindle with it to operate the train of gears, while when the pinion is turned in the direction of arrow a the dog will move around with the pinion without rotating the spindle. The spindle 32 is further provided with a gear 44, meshing with a pinion 45, fast on a governor-shaft 46, upon which is mounted a governing device 47, composed of two sleeves 48 and 49, connected by leaf-spring parts 50, provided with weights 51. The sleeve 49 is provided with a disk 49^a, adapted to engage a brake-lever 52 of the bell-crank type and fulcrumed as shown at 52^a. In case there is a tendency for the mechanism to operate too fast under the influence of the power-spring the centrifugal force of the weights 46 causes the sliding sleeve 49 to move in the direction of the transverse center of the spindle, whereby the disk 49^a will be made to engage one arm of the pawl 52, the other arm being acted on by the set-screw 53, whereby the brake-lever may be set to apply the brake as desired. From the foregoing description the use and operation of my improved device as thus far described may be explained as follows: Assuming that the spring 37 is wound up and placed under tension, the recoil of this spring

will act to set in motion the gears 34 and 33, the spindle 32, the gears 31 and 30, the spindle 28, the gear 27, the spindle 12, and consequently the contact-arm 16 and the hand or pointer 15. This mechanism is so adjusted and arranged that the hand or pointer 15 and the contact-arm 16 will move around the dial of the device, as well as around the ring 20, once during each twenty-four hours, and consequently will close the circuit wherever the contact 18, carried by the arm 16, engages a portion of the ring 20, provided with the segmental plates 23. The owner of the device may of course have a number of these segmental plates sufficient to cover the entire ring on the side opposite the continuous conducting-plate 22. Where my improved device is to be employed, it is assumed that it is not desirable to maintain the circuit in contact during the whole twenty-four hours. The segmental plates 23 will therefore be applied to the portion of the dial corresponding with the period of the day during which the lights are to be burned. This is illustrated in Fig. 2, as heretofore stated.

In the form of construction shown in Fig. 7 the ring for making and breaking the circuit through the instrumentality of the contact 18 is arranged to utilize a two-phase circuit. Consequently I employ three insulating members 54, 55, and 56, the central ring 56 being separated from the rings 54 and 55 by the conducting-rings 57 and 58, respectively. To each one of the outer insulating-rings 54 and 55 are attached the segmental plates 23, which are substantially of the same construction shown in Figs. 2 and 4. In this case the contact-arm 16 is provided with two contact members 16^a and 16^b, one of which bridges the insulating-ring 54 and engages the conducting-ring and the segmental plate 23, while the other member 16^c bridges the insulating-ring 55 and bridges the space between the ring 58 and the other segmental plates 23. In this case, assuming that the current passes from one pole of the source (not shown) to the plate 57 through a wire 59, it will pass thence to the member 16^a of the contact, thence to one of the segmental contact-plates 23, thence through the wire 60 to the opposite contact-plate 23, thence to the opposite contact member 16^c, and thence to the conducting-ring 58 and through the conductor 59^a to the other pole of the electrical source. (Not shown.)

Having thus described my invention, what I claim is—

1. In an electric time-switch, the combination with a motor, of a ring comprising a continuous conducting member, a number of removable contact-plates connected to form a conducting - segment, the continuous ring member and the segmental member being insulated from each other, circuit-wires connected with the respective members, and a

contact connected to be rotated by the motor and constructed to electrically connect the two members and close the circuit while passing the segmental member of the ring.

2. In an electric time-switch, the combination of a circular conducting member, a segmental conducting member composed of a number of separable parts, the segmental member being arranged in parallel relation with the circular member but insulated therefrom, a circuit-closing contact arranged to bridge the insulation and connect the two members to close the circuit while passing the segmental member, and means for actuating the contact.

3. The combination of a circular conducting member, a segmental conducting member arranged in parallel relation with the circular member, an insulating member separating the two conducting members, a time-measuring motor, a hand or pointer connected in operative relation therewith, a time-graduated dial over which the hand or pointer member moves, and a circuit-closing contact actuated by the motor and moving in unison with the hand or pointer and forming an electrical connection between the two conducting members, while the hand or pointer is moving over the portion of the time-graduated dial corresponding with the segmental member.

4. In a structure of the class described, the combination of a casing, a hinged door provided with a dial graduated and marked to indicate time in suitable subdivisions of a day, a time-measuring motor, a hand or pointer connected to be actuated by the motor and arranged to move in proximity to the time-indications of the graduated dial, a ring mounted on the casing and composed of a continuous conducting member, a segmental conducting member, and an insulating member separating the conducting members, the segmental conducting member being composed of a number of parts arranged with reference to the time-subdivisions indicated on the dial, and a contact connected to be operated by the motor and arranged to move in unison with the hand or pointer, the contact being constructed to bridge the insulating material and connect the two conducting members to close the electrical circuit when the contact and the pointer are moving through the portion of the arc of a circle corresponding with the length of the segmental conducting member.

5. In apparatus of the class described, the combination of a casing, a spring-actuated time-measuring motor, a governor for controlling the speed of the motor, a main spindle, a hand or pointer connected with the spindle, a dial upon which are marked time-subdivisions located adjacent to the pointer as the latter rotates through the instrumentality of the motor, a stationary ring com-

- posed of a continuous conducting member, a segmental conducting member and an insulating member, and a contact connected to move with the spindle which actuates the hand or pointer and whose outer extremity engages the ring and is provided with a conducting part adapted to bridge the insulating member and connect the two conducting members to close the circuit while moving through the arc corresponding with the length of the segmental member.
6. In apparatus of the class described, the combination of a casing, a ring located in the casing and composed of a continuous conducting member, a segmental member composed of a plurality of separable parts, a dial upon which are indicated time-subdivisions, the parts of the segmental member being arranged with reference to the time-subdivisions of the dial corresponding with the portion of the arc through which the segmental conducting member extends, a motor, a hand or pointer actuated by the motor and arranged to move adjacent to the time-subdivisions of the dial, and a contact connected with the motor to move in unison with the hand or pointer, the contact being constructed to bridge the insulating member of the ring and electrically connect the two conducting members when the contact and pointer are moving through the arc corresponding with the length and position of the segmental conducting member.
7. In apparatus of the class described, the

combination of a casing, a dial upon which are indicated time-subdivisions, a revoluble spindle, a hand or pointer carried by the spindle and arranged to move around the dial when the spindle is rotated, a ring mounted in the casing and composed of a continuous conducting member, a segmental conducting member, and an insulating member separating the two conducting members, a contact connected with the spindle which actuates the pointer and arranged to move in unison therewith, the contact being arranged to bridge the space between the two conducting members and electrically connect the latter when the contact together with the hand or pointer, is moving through the arc corresponding with the segmental conducting member, a spindle journaled in the casing, a spring connected with the latter to rotate the same, and a gearing connection between the spring-actuated spindle and the spindle actuating the hand or pointer and the contact, means for winding the spring to place the latter under tension without operating the hand or pointer and the electrical contact, and suitable means for governing the speed of the motor for the purpose set forth.

In testimony whereof I affix my signature in presence of two witnesses.

CLAUDE E. MENTZER.
